INKING MECHANISM FOR PLATEN
PRINTING PRESSESCharles F. Root, Cleveland, Ohio, assignor to
The Chandler & Price Company, Cleveland,
Ohio, a corporation of Ohio

Application November 23, 1944, Serial No. 564,764

12 Claims. (Cl. 101—341)

1

The present improvements, relating as indicated to inking mechanism for printing presses, have more particular regard to inking mechanism for platen printing presses of the so-called Gordon type. Still more particularly the present invention relates to improvements in the inking mechanism which forms the subject matter of my co-pending application filed January 13, 1944, Serial No. 518,105.

It will be understood, however, that as in the case of the invention which forms the subject matter of such co-pending application, so the present improvements may be advantageously used with printing presses of other types where a form requires to be inked by transferring ink from a suitable fountain or like source spaced from such form.

One principal object of the present invention is to provide readily adjustable means whereby the fountain or roller which forms a part thereof and which supplies ink to the distributing rollers may be variously positioned depending upon whether the press is being operated normally, i. e. actually printing, or for make-up purposes. At the same time provision is made so that whenever the throw-off is applied to the press so as to interrupt the printing operation the supply of ink from the fountain roller to the distributing rollers will likewise be automatically interrupted. Still another object is to provide means whereby the amount of ink transferred by the fountain roller to the distributing rollers may be varied lengthwise of the latter so as correspondingly to vary the supply of ink to different portions of the form, as is desirable where one such portion has a more extensive printing face than the other.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a side elevation of the bed member of a platen printing press of the Gordon type showing my improved inking mechanism associated therewith;

Fig. 2 is a similar side elevation on a larger scale of such inking mechanism showing its operative connections with the press;

2

Fig. 3 is a plan view of such mechanism, i. e. as viewed from above in Fig. 2;

Fig. 4 is a rear elevation of the same, with certain parts shown sectioned, on the plane indicated by the line 4—4 of Fig. 2;

Fig. 5 is a transverse and Fig. 5a a vertical section of another operative part of such inking mechanism, the plane of such transverse section being indicated by the line 5—5 Fig. 2; and

Fig. 6 is a side elevation corresponding to that of Fig. 2 but showing certain selected parts only of the inking mechanism.

As indicated, it has been deemed necessary for the purpose in hand to illustrate only those portions of the press with which my improved inking mechanism is directly associated. As further indicated, the press chosen for illustrative purposes is of the so-called Gordon type.

Thus the bed 1 of the press, in the face of which the form (not shown) is secured in familiar manner, is oscillatorily supported at its lower end about an axis 2 in the main frame 3 of the press. Oscillation of bed 1 is produced by means of connecting rods or side arms 4, one on each side, which are attached at one end to cranks (not shown) on a rotating part of the press and at the other to the corresponding ends of a shaft 6 that extends transversely through the bed. The last-named connections include eccentrics so that by oscillation of the shaft, the bed may be displaced sufficiently so as to prevent the form from coming into contact with the platen. Such shifting of the eccentric connections just referred to is ordinarily effected by means of hand lever (not shown) through an interconnected system of links and levers 9.

Also oscillatorily mounted on shaft 6 are roller frames 10, one on each side of the bed, which carry the form inking rollers 11. The latter are mounted in the usual manner in trucks or saddles 12 which are in turn attached to the outer end of plungers 13 that are normally drawn inwardly by associated springs in arms 10. Oscillation of the latter is produced in the usual manner as by means of a link 14, illustrated in fragmentary form only in Fig. 1, which is connected at one point with a pivot 14a on one of said arms, spaced from the axis of oscillation thereof, and at the other end to a fixed point on the main frame 50 of the press.

Mounted on a bracket 15 that projects upwardly from bed 1 is an ink distributing plate 16 which is preferably in the form of a disc rotatable about a central pivot on said bracket. To assist in the even distribution of ink on the disc, pro-

vision is usually made for imparting to the latter a step-by-step rotative movement, but such means form no part of the present invention and are therefore not illustrated. The plane of the disc is desirably inclined at an oblique angle to that of the form and extending along the respective sides of said disc and form are tracks 17 which constitute in effect a continuous trackway whereon the previously described form inking rollers 18, as well as the ink distributing rollers 18, are movably distributed.

The detailed construction of the main trackway and of said form inking and ink distributing rollers constitutes no part of the present invention, and their operation, so far as the present improved inking mechanism is concerned, may be taken as the same as in the conventional Gordon type press. In other words, the uppermost of the ink distributing rollers 18, as the latter are moved back and forth across the ink distributing plate 16, is brought into contact with the inking roller 20 of the ink well 21, description of which follows, and the ink received therefrom is thereupon distributed uniformly over the plate during downward travel of the distributing rollers. Upon reverse movement of the latter the form rollers are swung upwardly across the plate, take up the film of ink thus distributed thereon, and as they move downwardly across the form, ink the latter.

As best shown in Figs. 2, 3 and 4, the ink fountain 21 as a whole is carried by a frame which comprises two similar side members 22 held together in spaced-apart relation by means of rods 23, the roller 20 together with the usual scraper blade 24 which forms the bottom of the fountain being mounted between said side members. The latter include similar forwardly extending arms 25 that are pivoted about a shaft 26 in the bracket 15 which carries the disc 16. In its normal position the fountain is swung upwardly about the pivotal axis provided by shaft 26 so as to bring the inking roller 20 into position to contact with one or both of distributing rollers 18; however, upon dropping the fountain even slightly, such inking roller will be moved out of such contacting position.

Shaft 6, as previously described, is designed to be oscillated through the throw-off so that by means of its eccentric connections with the side arms 4 the form will be held out of contact with the platen. Such oscillation of shaft 6 is also utilized simultaneously to control the position of the ink fountain through means now to be described.

Mounted for oscillation upon the same shaft 6 to which the ink fountain is swingably connected through arms 25 is a rocker comprising two arms 30 and 31 rigidly connected together through the medium of a short stub-shaft 32 (see Fig. 4), to which said arms are pinned, such shaft also carrying an adjusting screw 33, the head of which is disposed so as to contact with the lowermost rod 23 that forms a part of the ink fountain frame. The lower end of rocker arm 30 extends downwardly and carries a roller 34 disposed to contact with a ring 35 that is mounted for rotative adjustment upon the adjacent end of shaft 6. This ring is concentric with the axis of the shaft and is formed with a radially projecting boss 36 that extends in the form of a segment part way around the ring. By means of a spring-pressed ball 37 disposed to engage in one or the other of three openings or depressions 38, 39 and 40 in said ring the latter may be secured in any

one of three different rotative positions upon the shaft end in question, a knob 41 being provided on the ring to facilitate its adjustment in selected position. A radially projecting pin 42 prevents rotation of the ring too far in either direction.

Under normal operating conditions of the press, eccentric shaft 6 will occupy the position shown in Fig. 2 and likewise the position of ring 35 will be as shown in said figure in which the central depression 36 is in engagement with the spring catch 37. The location of the boss 36 on the ring is such that in this position of the parts roller 34 on rocker arm 31 will be engaged therewith and the rocker accordingly actuated to support the ink fountain in position where the fountain roller 20 will be adapted to contact with one or both of the rollers 18 when the latter reaches the limit of its travel toward the fountain. However, when shaft 6 is oscillated to its throw-off position, such oscillation being in a counter-clockwise direction as viewed in Fig. 2, boss 29 will be rotated out of engagement with roller 34 and the rocker, together with the fountain supported thereby, will be dropped a sufficient distance to prevent such contact between the fountain roller and said rollers 18. As a result no ink will be transferred to the inking disc when the press is in throw-off position, i. e. running but not printing.

Under certain conditions in setting up the press for operation it is found desirable to run the press with the throw-off on or off but without inking the form. In such case, by rotating ring 35 to bring depression 40 in engagement with the spring catch, the roller 34 on the rocker arm 31 will not be engaged by the boss 36 at any time. On the other hand, under other conditions it may be desired to ink the form with the throw-off operative. In such case, by rotating the ring in the opposite direction until aperture 38 is engaged by the spring catch, said roller 34 will remain at all times in engagement with the boss 36.

The portions 45 of tracks 17 on which the trucks that carry the ink rollers 18 run are disposed one on each side of the inking disc and necessarily extend beyond the latter to the ink fountain in order that contact may be made by said rollers with the fountain roller 20. As best shown in Fig. 6, these track extensions 46 are hingedly connected with the main track portions and are capable of being independently vertically adjusted by means of set screws 47. By varying the adjustment of these screws such track extensions may be raised or lowered to obtain the desired degree of contact between the two rollers, and such degree of contact may also be varied longitudinally of the axes of the rollers. By introducing variation in such degree of contact, more or less ink may be transferred from the fountain roller to the inking roller and from the latter in turn to the inking disc, at one side of such disc or the other as may be found desirable. In other words, where a more extensive printing surface occurs on one side of the form, a correspondingly greater amount of ink can be supplied to the same side of the disc and thus insure proper inking of the form without accumulating a surplus in any portion thereof.

Also by hingedly connecting track extensions 46 with the main tracks 17, such extensions may be turned upwardly entirely out of the way of the ink fountain when it is desired to secure access to the latter or remove the roller of the same for any purpose.

Step-by-step rotation of the fountain roller

is produced by means of a ratchet wheel 50 on one end of the roller shaft (the rear as viewed in Figs. 1 and 2) and a pawl 51 carried by a lever 52, which is pivoted on the end of the roller shaft. A link 53 connects the outer end of lever 52 with the adjacent side arm 10 of the press so that upon swinging movement of the latter said lever will be oscillated sufficiently to rotate the ratchet wheel an amount equal to the distance between the successive teeth thereon.

From the foregoing description it will be seen that the operator of a press of the type in question may quickly and easily adjust the inking mechanism to suit the conditions of normal operation and at the same time facilitate press make-up. When in course of normal operation the press throw-off is actuated the supply of ink to the ink distributing disc is immediately and automatically cut off. On the other hand, should it be desired to take proofs when setting up the press for a run, the inking mechanism may be rendered operative irrespective of whether the throw-off is actuated or not. Similarly, such inking mechanism may be rendered inoperative irrespective of whether the throw-off is actuated or not. Finally, by independently adjustably supporting the hinged track extensions over which the inking roller travels in order to contact with the fountain roller, the degree of contact between the two rollers may be readily varied as required.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In inking mechanism for printing presses, the combination of a fountain roller mounted so as to be tiltable into and out of position to contact with an ink-distributing roller, a rocker adapted to tilt said fountain roller, an oscillable shaft connected with the press throw-off, and a boss on said shaft adapted to engage an arm of said rocker, whereby the latter normally maintains said fountain roller in such contacting position and upon rotation of said shaft said roller is dropped into such non-contacting position, said boss being movable on said shaft into and out of position where it may thus engage said rocker.

2. In inking mechanism for printing presses, the combination of a fountain roller mounted so as to be tiltable into and out of position to contact with an ink-distributing roller, a rocker adapted to tilt said fountain roller, an oscillable shaft connected with the press throw-off, and a boss on said shaft adapted to engage an arm of said rocker, whereby the latter normally maintains said fountain roller in such contacting position and upon rotation of said shaft said roller is dropped into such non-contacting position, said boss being movable on said shaft into and out of position where it may thus engage said rocker, said boss in one such other position engaging said rocker irrespective of oscillation of said shaft.

3. In inking mechanism for printing presses, the combination of a fountain roller mounted so as to be tilttable into and out of position to contact with an ink-distributing roller, a rocker adapted to tilt said fountain roller, an oscillable shaft connected with the press throw-off, and a boss on said shaft adapted to engage an

arm of said rocker, whereby the latter normally maintains said fountain roller in such contacting position and upon rotation of said shaft said roller is dropped into such non-contacting position, said boss being movable on said shaft into and out of position where it may thus engage said rocker, said boss in one such other position remaining out of engagement with said rocker irrespective of oscillation of said shaft.

10   4. In inking mechanism for a printing press having a throw-off, the combination of an ink-distributing plate, an ink-distributing roller movable back and forth across such plate, an ink-fountain adjacent one edge of said plate, said fountain being pivoted about an axis beneath said plate and including a roller normally adapted to contact with said distributing roller when the latter is moved towards such edge, and means adapted to support said fountain with its roller in such contacting position, said means including a rocker extending beneath said fountain, whereon the latter rests, an oscillable shaft connected with the press throw-off, and a rotatably adjustable ring on said shaft carrying a boss adapted in one position of said ring to engage and disengage an arm of said rocker upon oscillation of said shaft.

15

20

25

30 5. In inking mechanism for a printing press having a throw-off, the combination of an ink-distributing plate, an ink-distributing roller movable back and forth across such plate, an ink-fountain adjacent one edge of said plate, said fountain being pivoted about an axis beneath said plate and including a roller normally adapted to contact with said distributing roller when the latter is moved towards such edge, and means adapted to support said fountain with its roller in such contacting position, said means including a rocker extending beneath said fountain, whereon the latter rests, an oscillable shaft connected with the press throw-off, and a rotatably adjustable ring on said shaft carrying a boss adapted in one position of said ring to engage and disengage an arm of said rocker upon oscillation of said shaft and in another position of said ring to engage such arm irrespective of oscillation of said shaft.

35 40 45

50 Said shaft.

55 6. In inking mechanism for a printing press having a throw-off, the combination of an ink-distributing plate, an ink-distributing roller movable back and forth across such plate, an ink-fountain adjacent one edge of said plate, said fountain being pivoted about an axis beneath said plate and including a roller normally adapted to contact with said distributing roller when the latter is moved towards such edge, and means adapted to support said fountain with its roller in such contacting position, said means including a rocker extending beneath said fountain, whereon the latter rests, an oscillable shaft connected with the press throw-off, and a rotatably adjustable ring on said shaft carrying a boss adapted in one position of said ring to engage and disengage an arm of said rocker upon oscillation of said shaft, in another position of said ring to engage such arm irrespective of oscillation of said shaft, and in another position of said ring to remain out of engagement with such arm irrespective of oscillation of said shaft.

60

65

70 7. In mechanism of the character described, the combination of an inking plate, an ink fountain including a roller disposed adjacent to one edge of said plate, an inking roller transversely movable across the latter into and out of contact with said fountain roller, and means adapt-

ed to vary the degree of contact of said rollers longitudinally of their axes.

8. In mechanism of the character described, the combination of an inking plate, an ink fountain including a roller disposed adjacent to one edge of said plate, an inking roller transversely movable across the latter into and out of contact with said fountain roller, parallel tracks disposed alongside said plate, wheels for said inking roller adapted to run on said tracks with said inking roller in contact with said plate, and extensions of said tracks for carrying said inking roller into contact with said fountain roller, said track extensions being adjustable to vary the degree of contact of said rollers longitudinally of their axes.

9. In mechanism of the character described, the combination of an inking plate, an ink fountain including a roller disposed adjacent to one edge of said plate, an inking roller transversely movable across the latter into and out of contact with said fountain roller, parallel tracks disposed alongside said plate, wheels for said inking roller adapted to run on said tracks with said inking roller in contact with said plate, and extensions of said tracks hingedly connected thereto for carrying said inking roller into contact with said fountain roller, said track extensions being adjustable to vary the degree of contact of said rollers longitudinally of their axes.

10. In mechanism of the character described, the combination of an inking plate, an ink fountain including a roller disposed adjacent to one edge of said plate, an inking roller transversely movable across the latter into and out of contact with said fountain roller, parallel tracks disposed alongside said plate, wheels for said inking roller adapted to run on said tracks with said inking

8
roller in contact with said plate, extensions of said tracks hingedly connected thereto for carrying said inking roller into contact with said fountain roller, and adjusting screws whereby the outer ends of said track extensions may be independently raised and lowered.

11. In inking mechanism for printing presses, the combination of a fountain roller mounted so as to be movable into and out of position to contact with an ink-distributing roller, adjustable means connected with the press throw-off and adapted in one position to move said fountain roller into such out-of-contact position upon actuation of such throw-off, and means operative to hold said adjustable means in another position unaffected by actuation of such throw-off.

12. In inking mechanism for printing presses, the combination of a fountain roller mounted so as to be movable into and out of position to contact with an ink-distributing roller, adjustable means connected with the press throw-off and adapted in one position to move said fountain roller into such out-of-contact position upon actuation of such throw-off, and means operative to hold said adjustable means in position to maintain said fountain roller in contacting position irrespective of such throw-off, when desired.
